(57) **CLAIM**

The ornamental design for a computer product, as shown and described.

DESCRIPTION

The computer product includes a face plate for a computer case. The computer case also includes a body secured to the face plate.

FIG. 1 is a top, front and right side perspective view of a computer product in accordance with a first embodiment of the invention;

FIG. 2 is a front view thereof;

FIG. 3 is a right side view thereof;

FIG. 4 is a top plan view thereof;

FIG. 5 is a left side perspective view thereof;

FIG. 6 is a rear plan view thereof; and,

FIG. 7 is a bottom plan view thereof.
